UNITED STATES PATENT OFFICE.

CHARLES MARCUS, OF NEW YORK, N. Y., ASSIGNOR, BY MESNE ASSIGNMENTS, TO BIJUR MOTOR APPLIANCE COMPANY, A CORPORATION OF DELAWARE.

DYNAMO-ELECTRIC APPARATUS.

1,373,901.

Specification of Letters Patent.

Patented Apr. 5, 1921.

Application filed June 27, 1918. Serial No. 242,157.

To all whom it may concern:

Be it known that I, CHARLES MARCUS, a citizen of the United States, and a resident of the borough of Queens, in the city and State of New York, have invented an Improvement in Dynamo-Electric Apparatus, of which the following is a specification.

This invention relates to dynamo-electric machinery, and with regard to the more specific features thereof, to such as are employed for current generation for motor vehicles.

One of the objects of this invention is to provide a practical and relatively inexpensive generator of the above type, whose output shall be suited to requirements under various conditions of operation.

Another object is to provide simple and easily adjustable means for maintaining a proper setting of a generator of the above type.

Another object is to provide means of the type last mentioned, compact in construction, accurate in action, and whose period of usefulness shall be long.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein are shown one or more of various possible embodiments of the several features of this invention, Figure 1 is an interior view of an end head of a generator embodying my invention.

Fig. 2 is a side view of my adjusting means mounted in position.

Fig. 3 is a detailed view of parts of said adjusting means.

Fig. 4 is a sectional view taken along the line 4—4 of Fig. 3.

Fig. 5 is a view in longitudinal section of an operating means for adjusting the third brush.

Figs. 6 and 7 are modified forms of operating means.

Fig. 8 is a face view on a smaller scale, of a modified form of washer for the embodiment shown in Fig. 7.

Fig. 9 is a view similar to Fig. 1 of a modified form of my invention.

Fig. 10 is a front view of the exterior of the end head shown in Fig. 9 and Fig. 11 is a fragmentary view in longitudinal section of my generator showing the mounting of the automatic switch.

Fig. 12 is a detail sectional view along the line 12—12 of Fig. 9.

Similar reference characters refer to similar parts throughout the different views of the drawings.

As conducive to a clear understanding of my invention, it may be pointed out that as motor vehicles are ordinarily operated during the summer time with a much smaller current consumption for lighting and the like than in the winter, a generator regulated for proper current production in the summer may produce insufficient current to maintain the battery in a proper state of charge during winter operation, and vice versa, if the generator be regulated for proper operation in cold weather, its rates of output may be excessive for warm weather use, to the damage of the battery. By my invention I provide a simple and easily operated means for securing a proper setting of generators of the type in which automatic regulation is secured by the connection of the field coil to a brush offset from neutral position called a third or extra brush. I secure proper operation for different conditions of use, broadly by providing for a ready shifting of the position of the extra brush so that the potential difference between the field terminals and the consequent output of the machine may be varied.

Thus, if the vehicle is to operate under conditions where an increased output is necessary the extra brush would be shifted to provide for a greater potential difference between the field terminals and vice versa where a lesser output would be required.

Referring now to Fig. 1 of these drawings, there is shown an end head 1 of a four pole generator and the outline of its commutator 2. Disposed at neutral points are main brushes 3 and 4 of any desired construction. These brushes are shown one mounted in each of two brush boxes 5 secured to the end head as by screws 6 and 7 and the brushes are urged for suitable pressure against the commutator by springs 8. The main brush

construction and manner of mounting need not be described in greater detail as my present invention does not reside therein.

My extra or third brush is shown at 9 and is preferably rigidly mounted on an adjustable brush plate 10. The extra brush 9 is insulated from brush plate 10, the brush plate having an elongated opening 11 therein which is completely filled by a corresponding piece of insulation 12. On one side of plate 10, there is another piece of insulation 13 which preferably extends beyond said opening as shown at 14 and on the opposite side of plate 10 there is a further piece 15 of insulation 15 which is wider than opening 11 and extends beyond both of its sides as shown in Fig. 3. On insulating plate 13, there is supported a metallic brush rest 16 with an upturned portion 17. Brush box 18 is preferably made of sheet metal has its sides extending through brush rest 16, insulating plate 13, 12 and 15 and a back plate 19 over which the ends of brush box 18 are bent as shown at 20. The sides of the brush box 25 preferably have integral lugs 21 resting on brush rest 16, so that brush box 18, not only serves to hold brush 9, but also acts as a securing means for retaining plates 16, 13, 12, 15 and 19 together near one end. A staked screw 22 serves to hold said plates together at the other end, there being a circular opening 110 in brush plate 10, completely filled by a piece of insulation 22' through which screw 22 passes. Brush 30 plate 10 is preferably formed with a second opening 11' identical with opening 11, openings 11 and 11' being preferably formed symmetrically with respect to a diameter of the machine bisecting opening 110. By 40 this arrangement it is possible by the use of the same parts to assemble my third brush unit with the brush in either of two positions on the plate 10, thus adapting one construction to different rotations of machines. Secured to upstanding portion 17 of the brush rest, there is a coil spring 70 whose end presses on brush 9, maintaining it in contact with the commutator at the proper pressure.

45 The brush plate 10 is preferably formed with two slots 23 and 24, one near each end, which slots are formed generally in an arcuate shape to permit a shifting of the plate 10 and with it of the brush 9 in an arc having the axis of the machine as its center. The interior of the end head of the machine is formed with lugs 25 on which said plate rests and to which it is secured by screws 26, one passing through each of the arcuate 50 slots 23 and 24. Screws 26 as is apparent constrain the brush plate 10 when shifted to follow a circular path about the center of the machine and thus limit the brush to a similar path.

55 To effect adjustment of the extra brush,

I preferably provide on the outer edge of brush plate 10 an integral rack 27 which rack extends generally along a circular arc. Coöoperating with said rack 27, there is a pinion 28 preferably operable from the exterior of the machine by means now to be fully described.

One embodiment of this means is shown in Fig. 5. The third brush adjusting pinion is shown in this figure resting against 75 the interior surface of the end head and formed with an integral circular flange 30 extending into circular opening 29 in the end head. A flanged bushing 31 is fitted into opening 29 from the exterior of the end head 80 having its flange resting against shoulder 32 and having, also, an interior flange 33 encircling bolt 34, which bolt extends through the bushing and is threaded to the interior of the pinion as at 35, the bolt being 85 formed with a fillister head as shown at 51. The bushing is preferably keyed to the pinion as shown at 36 and a coil spring 37 preferably surrounds the shank of bolt 34, one end pressing against the head of said bolt 90 and the other against the inturned flange 33 of the bushing. The spring thus acts to urge flange 31 of the bushing against the coöoperating shoulder, and the pinion 28 against the interior of the end head, thus 95 keeping the pinion from accidentally turning. A lead slug 38 preferably closes the opening in the end head and is formed with some distinguishing mark therein which must be destroyed as is obvious when adjustment is attempted. Tampering without detection by unauthorized persons is thus avoided.

In Fig. 6, I have shown a modified device for operating the pinion 28'. I have here 105 provided a setting key 39 readily operable from the exterior of the machine. The general construction of this modified device as is seen is closely similar to that of Fig. 5 and elements corresponding to those of Fig. 110 5 have been supplied with the same reference numerals as Fig. 5 primed. Bushing 31' in this modification preferably extends beyond the exterior surface of the end head as shown and key 39 preferably has a flange 40 fitting 115 over said extending portion, there being co-operating corrugations 41 on coöoperating faces of bushing 31' and key 39 whereby turning of the key will effect turning of the 120 bushing and consequently turning of the pinion. The key 39 is preferably provided with an interior ledge 42 encircling bolt 34' and the key is guarded against coming off the construction by a nut ring 43 provided with a fillister 51', within the exterior of 125 the key and secured therein by a lock washer 44. A lead slug 38' similar to lead slug 38 in Fig. 4, here also guards against tampering. Referring to Fig. 1, it is noted that key 39 is preferably located between stops 130

52 and 52' on the end head which confines the amount of adjustment between proper limits. An authorized person may bring about adjustment beyond such limits, if desired, by removing the key and turning bolt 34' by means of a separate tool.

In Fig. 7, I have shown another modification of my pinion-operating device. In this case, the pinion 28² is formed rigid with 10 pinion operator 45 preferably by staking, said operator extending through an opening in the end head and being provided with a shoulder 46 resting on a corresponding shoulder in the end head. A coil spring 37² 15 preferably encircles the operating member 45 with one end resting against washer 47 in contact with pinion 28². The operating member 45 with its attached pinion and encircling spring may be inserted as a unit 20 through the exterior face of the end head and the two halves 48 and 49 of a flanged split washer are then to be placed in position, as shown in Fig. 7 with flanged portion 50 resting against a corresponding shoulder 50' 25 on the operating rod, so that one end of the spring rests against said split washer. In this modification, also, I preferably provide a lead slug 38² for the purpose described in connection with Fig. 5. Although there are 30 special benefits in the use of split washer 48, 49, I prefer to employ the unitary washer 69 shown in Fig. 8. This washer has a radial slot 70' adapted to be slipped over operator 45, and an integral flange 71 corresponding to flange 50 on the split washer.

It is to be understood that if desired, an operating lever may be applied to the modification shown in Fig. 7 in a manner similar to Fig. 6.

40 The operation of the above described embodiment of my invention is substantially as follows:

If in the use of the embodiment shown in Fig. 5, the generator does not produce 45 enough current to keep the battery in proper condition, an authorized person moves the extra brush 9 in a direction to cause an increased potential between the field terminals. To bring this about he destroys the lead seal 50 and inserts a screw driver or other tool in the fillister head 51, turning the screw driver to the proper extent in the proper direction, and with it bolt 34, thus rotating the pinion 28 and bushing 31 overcoming the friction 55 between the contacting surfaces of the pinion and bushing with the end head. Pinion 28 is thus turned through a sufficient angle and in the proper direction to bring about a proper setting of the generator.

60 The operation of the embodiment shown in Fig. 7 is similar to that just described, except of course, that the friction to be overcome is at the contacting surfaces of operator 45 and washer 48, 49 or 69 with the 65 end head.

In case the modification shown in Fig. 6 is employed, the owner or operator of the vehicle himself, by a simple shifting of lever 39 may effect proper adjustment. One extreme position of the lever L is generally 70 suitable for summer use, and the other extreme position for cold weather use, and when used only in such extreme positions at proper times the device will ordinarily operate satisfactorily. Of course, the lever 75 may also be placed in any intermediate position to accurately suit the device to various conditions of operation.

It is to be noted that by the action of the spring in each of the embodiments shown in 80 Figs. 5, 6 and 7, the pinion is held in such firm frictional engagement with the end head and associated parts that it offers a substantial resistance to turning. For this reason, the extra brush when adjusted to 85 any desired position will maintain its adjustment in spite of vibration. The pinion acts as a locking means for the brush plate and its corresponding brush as no shifting of the latter can take place without a corresponding 90 turning of the pinion.

If I attempt to avoid unintended change of setting by unintended shifting of the extra brush by a relatively tight securing of the brush plate, it is clear that in attempting 95 to effect adjustment, there will be a substantial strain on the co-operating teeth of the pinion of the gear with a possibility of distortion, breaking or excessively rapid wear 100 of the gear teeth with consequent necessity for repair or replacement.

In Figs. 9 to 11, is shown a different embodiment of certain features of this invention. In Fig. 9, as in Fig. 1, main brushes 3' and 4' are disposed substantially as in 105 Fig. 1 corresponding parts bearing the same reference numerals as in Fig. 1 primed.

I preferably arrange my third brush on a bracket plate 53, one end of which is preferably secured by the same screw 54 which 110 serves to maintain one of the main brush brackets in position and the other end of which is rigidly secured in the end head by screw 55. This bracket is preferably formed with an arcuate slot 56, the center of whose 115 arc is at the axis of the machine. The third brush assembly is preferably secured in said arcuate slot as shown in Figs. 9, 10 and 12 and as described below. On one face of bracket 53, there is an insulating plate 57 120 on which is laid metallic third brush rest 58. The third brush box 59 is preferably formed with integral flanges 60 and screws 61 serve to secure the unit to bracket plate 53, said screws passing through brush box flange 60, 125 brush rest 58, insulating plate 57, opening 56 in bracket 53, and washers 62, nut 63 securing the entire unit in assembly.

The end head is preferably formed with an arcuate opening 64 registering with the 130

third brush unit. Nuts 63 are accessible through this opening. The opening is preferably covered by a sheet metal inclosure 65 secured in position by screws 66 preferably 5 covered by lead slugs as and for the purpose of slug 38 in Fig. 5.

When adjustment of the position of the third brush is desired an authorized person removes cover plate 65, loosens nuts 63 and 10 shifts the third brush unit within slot 56 until the third brush is in the proper position whereupon he again tightens nuts 63 and replaces the cover plate 65.

In Figs. 9 and 11, I have also shown an 15 automatic switch 67 disposed within the end head 1 between main brush unit 3' and bracket 53. The detailed construction of this automatic switch is no part of my present invention and need not be set forth, it 20 may simply be noted that switch 67 is preferably one of the automatic electro-magnetic type and that its function is to automatically establish a circuit between the generator and the storage battery when the voltage of the 25 former is appreciably in excess of that of the latter, and to automatically break said circuit when the battery would otherwise discharge its current into the generator. As shown in Fig. 10, this main switch unit is 30 secured to the face of the end head by screw 68 and extends between the commutator and the curved surface of the end head, there being sufficient clearance for proper operation.

35 It will thus be seen that there is herein described apparatus in which the several features of this invention are embodied, and which apparatus in its action attains the various objects of the invention and is well 40 suited to meet the requirements of practical use.

As many changes could be made in the above construction, and many apparently widely different embodiments of this invention 45 could be made without departing from the scope thereof, it is intended that all matter contained in the above description or shown in the accompanying drawings shall be interpreted as illustrative and not in a 50 limiting sense.

Having described my invention, what I claim as new and desire to secure by Letters Patent is:

1. In an extra brush generator, in combination, an end head, main brushes, a plate, studs in said end head passing through acute slots in said plate, for permitting adjustment of said plate, an extra-brush box insulatedly supported by said plate, an extra brush in said box, an arcuate rack on 55 said plate, a pinion operable from the exterior of said end head, to adjust the position of said extra brush and means apart from said plate and said rack for resisting rotation of said pinion.

2. In an extra brush generator, in combination, an end head, main brushes, an extra brush, means comprising coöperating elements one movable with said extra brush, and one operable from the exterior for adjusting the position of said extra brush and means coacting with said means last mentioned, and through said coöperating elements for securing said extra brush in any position in which it is set. 70

3. In an extra-brush generator, in combination, main brushes, an extra brush, a support for said brush, said support having a rack thereon, a coöperating pinion always in engagement with said rack, and operable from the exterior to permit adjustment of said extra brush, and means separate from said rack for offering a substantial resistance to the turning of said pinion. 75

4. In an extra-brush generator, in combination, main brushes, an extra brush, gearing operable from the exterior for adjusting the position of said extra brush, and resistant means interposed between the point of application of force for adjustment, and 80 said gearing.

5. In an extra-brush generator, in combination, main brushes, an extra brush, a gear element operably connected to said extra brush, a coöperating gear element always in engagement with said first element, and operable from the exterior to permit adjustment of said extra brush, and a spring offering resistance to the operation of said 95 second gear element and retaining said first gear element against undesired displacement by reason of the meshing of said gear elements.

6. In an extra-brush generator, in combination, main brushes, an extra brush, a gear element operably connected to said extra brush, a coöperating gear element always in engagement with said first element, means whereby said second gear element may be 105 operated from the exterior, and a spring interposed between said last means and said second gear element, for offering resistance to the operation of said element. 110

7. In an extra-brush generator, in combination, main brushes, an extra brush, a rack operably connected to said extra brush, a coöperating pinion always in engagement with said rack, means whereby said pinion may be operated from the exterior, and a spring interposed between said means and said pinion, whereby said rack will not accidentally 120 shift its position, and whereby operation of said pinion will not place excessive strain on the coöperating gear teeth.

8. In an extra-brush generator, in combination, a non-rotatable element, main brushes, an extra brush, means operably connected to said extra brush, and a coöperating means always in engagement with said first means, said second means being 125 130

- strongly biased toward said element, and operable from the exterior to operate said first means to adjust the position of said extra brush.
- 5 9. In an extra-brush generator, in combination, an end head, main brushes, an extra brush, a rack operably connected to said extra brush, and a coöperating pinion always in engagement with said rack, strongly 10 biased toward the exterior of said end head, and operable from the exterior.
10. In an extra-brush generator, in combination, an end head, main brushes, an extra brush, a rack operably connected to said extra brush, a coöperating pinion inside 15 said end head, and always in engagement with said rack, means extending to the exterior of said end head, whereby said pinion may be operated, and a spring between said 20 means and said pinion, for placing said pinion in relatively tight engagement with the interior of said end head.
11. In apparatus of the character described, in combination, a third brush adjusting pinion, an end head having an opening with a shoulder, a bushing in said opening resting on said shoulder, said pinion resting against the inside of said head and being keyed with respect to said bushing, a 25 screw attached to said pinion, and a spring 30 adapted to urge said bushing and said pinion toward each other.
12. In apparatus of the character described, in combination, a third brush adjusting pinion, an end head having an opening with a shoulder, a bushing on said opening, resting on said shoulder, said pinion resting against the inside of said head and keyed with respect to said bushing, a screw 35 secured to said pinion, a coil spring within 40 said bushing, and adapted to urge said bushing and said pinion toward each other, a lever keyed to said screw, a nut securing said lever to said screw, and a lead slug covering 45 said nut.
13. In an extra-brush generator, in combination, an end head, main brushes, an extra brush, a bracket plate having an arcuate slot, means for insulatedly securing said extra brush with respect to said slot, said 50 means being accessible through an opening in said end head to adjust the position of said brush, and a sealed cover for said opening.

In testimony whereof I have signed my name to this specification this 6th day of 55 June, 1918.

CHARLES MARCUS.
